(57) **CLAIM**

The ornamental design for a welding saw blade, as shown and described.

DESCRIPTION

FIG. 1 is a perspective view of a welding saw blade showing my new design.

FIG. 2 is a front view of a welding saw blade.

FIG. 3 is a rear view of a welding saw blade.

FIG. 4 is a left side view of a welding saw blade.

FIG. 5 is a right side view of a welding saw blade.

FIG. 6 is a top view of a welding saw blade; and,

FIG. 7 is a bottom view of a welding saw blade.
